(57) **CLAIM**

The ornamental design for a table storage system, as shown and described.

DESCRIPTION

FIG. 1 is a perspective view of a table storage system showing my new design;

FIG. 2 is a front elevational view thereof,

FIG. 3 is a side elevational view thereof; and,

FIG. 4 is a bottom plan view thereof.

The broken-line disclosure in the views is for illustrative purposes only and forms no part of the claimed design.

1 Claim, 3 Drawing Sheets

FIG. 1

FIG. 2

FIG. 4

FIG. 3
